UNITED STATES PATENT OFFICE.

REINHOLD LÖFFLER, OF BERLIN, GERMANY, ASSIGNOR TO ACTIEN GESELLSCHAFT
FÜR ANILIN FABRIKATION, OF BERLIN, GERMANY.

STEAM TRAP.

1,426,205.

Specification of Letters Patent. Patented Aug. 15, 1922.

Application filed March 23, 1922. Serial No. 546,188.

To all whom it may concern:

Be it known that I, REINHOLD LÖFFLER, residing at Berlin, Germany (my post-office address being Taborstrasse 15, Berlin So. 33, 5 Germany), have invented certain new and useful Improvements in Steam Traps, for which I have filed application for patent in Germany, Sept. 30, 1920, and in England Feb. 27, 1922, and of which the following is 10 a specification.

The invention relates to a steam trap of the kind having its outlet valve controlled by means of a closed float and lever. The invention consists in the particular construction of the outlet valve and is illustrated in the accompanying drawings in which Figs. 1 and 2 are vertical sections in planes at right angles to each other through the trap, and Fig. 3 is a detail view drawn to an 15 enlarged scale.

The trap consists of the casing *a* in which there are constructed two outlet valves *b*, formed as labyrinths and controlled by the float *c*. These valves consist of the fixed 20 tubular part *d* having equidistant discs *e*, and the sleeve *f* adapted to turn on the axis of the part *d* and having internal annular ribs *g* extending between the discs *e*. In the 25 discs *e* and the ribs *g* are perforations *h* adapted to register with each other; normally, however, the perforations in discs *e* 30 are at an angle α to those in ribs *g*.

The steam or water or both enters at *i* and water collects in the casing *a*. As the quantity of this water increases the float rises and turns the sleeve *f* of the outlet valve *b*. Presently the perforations *h* register with each other, whereupon the passage for the 35 exit of water is free. According to the quantity of the water the perforations *h* register more or less; when they are out of register there is only a labyrinthine passage through which the steam or water can be forced. The annular ribs *g* slide against the part *d* 40 and the discs *e* against the sleeve *f* so that at these places neither steam nor water can pass.

Having now described my invention and the manner in which it may be performed 45 what I claim is,—

1. In a steam trap, the combination of a tubular member carrying a plurality of axially spaced external disks, a cylindrical member having a plurality of internal annular ribs positioned to take up the spaces 55 between said disks, the said disks and ribs having perforations adapted to register to define a passage, means defining a conduit between said passage and the tubular member and means for angularly moving the 60 tubular member and the cylindrical member relatively to one another.

2. In a steam trap, the combination of a tubular member carrying a plurality of axially spaced external disks, a cylindrical 65 member having one end closed and having a plurality of internal annular ribs positioned to take up the spaces between said disks, the disks and ribs having perforations co-operating in one relative angular position 70 of the tubular member and the cylindrical member to define a passage, means between the closed end of the cylindrical member and tubular member defining a conduit between the latter and the passage and means connected with the closed end of the cylindrical member for rotating it about the tubular member. 75

3. An article of manufacture, comprising a tubular member carrying a plurality of 80 axially spaced external disks having aligned perforations, a cylindrical member having a plurality of internal annular ribs positioned to take up the spaces between the disks, the ribs having aligned perforations adapted to 85 be aligned in one relative angular position of the tubular member and the cylindrical member with the perforations in the disks and form therewith a passage and means between the cylindrical member and the tubular member defining a conduit between the latter and the said passage. 90

4. An article of manufacture, comprising a tubular member carrying a plurality of axially spaced external disks having aligned 95 perforations, a cylindrical member having one end closed and having a plurality of internal annular ribs positioned to take up the spaces between said disks, the ribs having aligned perforations adapted to be aligned 100

in one relative angular position of the tubular member and the cylindrical member with the perforations in the disks and form therewith a passage and means in the closed 5 end of the cylindrical member for establishing a communication between the said passage and the tubular member.

In testimony whereof I affix my signature in presence of two witnesses.

REINHOLD LÖFFLER.
